UNITED STATES PATENT OFFICE.

GEORGE F. PEMBERTON, OF LINCOLN, CALIFORNIA, ASSIGNOR TO GLADDING, McBEAN & CO., OF SAN FRANCISCO, CALIFORNIA, A CORPORATION OF CALIFORNIA.

CONDUIT-TURNING MACHINE.

Application filed June 9, 1926. Serial No. 114,718.

This invention relates to conduit conveying and turning mechanism and especially to a machine for receiving conduits or tiles in a vertical position as they are formed from plastic material by being extruded through a die and conveying and depositing the same upon a platform in a horizontal position. It is the primary object of my invention to produce an improved machine for performing this function.

Briefly, my invention embodies a conduit receiving carrier and power means for reciprocally moving the carrier to and between a conveyor and platform. The carrier when adjacent the conveyor is adapted to receive a conduit in the upright position from the conveyor and cooperating means is provided for tipping the carrier as the same is moved toward the platform whereby the conduit will be deposited thereon in a horizontal position. Further means is provided for preventing movement of the conduit from the platform when the carrier returns therefrom. It is a further object of my invention to provide an improved mechanism of this type.

In the accompanying drawings I have illustrated certain specific embodiments of my invention, but it will be understood that the invention can be otherwise embodied and that the drawings are not to be construed as defining or limiting the scope of the invention, the claims appended to the specification being relied upon for that purpose.

Referring to the figures of the drawing: Fig. 1 is a side elevation of my improved machine.

Fig. 2 is a like view thereof showing the carrier in another position.

Fig. 3 is a sectional view taken on line III—III of Fig. 2.

Fig. 4 is a plan view of the machine.

In the drawings, 1 indicates the barrel or cylinder from which plastic material is forced through a die 2 to form a tile 3. The tile is received on a board 4, resting on a vertically movable plunger 5 and the tiling is cut off by a wire 6 when the tile has been extruded the proper length. The plunger 5 is adapted to move downwardly between the rolls of the conveyor 7, the board 4 being of a width to rest on the rolls of the conveyor. Beneath and extending downwardly from the conveyor 7 is a long gravity conveyor 8

extending to the tile receiving and conveying machine.

A carrier 9 is provided for receiving the tile from the conveyor 8 and depositing the same in a horizontal position on a platform 10. This platform rests on rollers 11 whereby the platform can be adjusted along to receive several tiles thereon. When the platform is fully loaded, a crane 12 carries the same to the stacking and drying part of the works.

One end of the carrier is provided with rollers 13 for receiving the tile on its board 4 and, when the carrier is in its vertical position at the end of the conveyor 8, these rollers 13 are slightly below the conveyor 70 rollers whereby the tile rides into the carrier by gravity. In its horizontal position, the carrier is supported on tracks 14 by rollers 15 on metal straps 16 riveted to the carrier.

The carrier is reciprocated to and between the conveyor 8 and platform 10 by a motor 17 through the following mechanism. The motor drives a shaft 18 through a belt 19, a hand wheel 20 being provided on the shaft 80 for manually adjusting the same. A worm 21 on the shaft 18 drives a worm wheel 22 on a shaft 23. A crank 24 on this shaft is connected by a connecting rod 25 to a cross head 26 slidable on tracks 27. Straps 28 rigid with the cross head, have their lower ends slotted at 29, which slots engage over trunnions 30 on the carrier.

The motor 17 operates continuously and the cross head is slowly moved reciprocally 90 to and between the conveyor 8 and platform 10. The crank arrangement causes a slight pause of the carrier at each end of its movement. During this pause at the conveyor 8 (Fig. 1), a tile 3 is guided into the carrier. 95 Return movement of the cross head pushes the carrier to the right at the trunnions 30, the carrier thereupon engaging against and tipping to the right about a roller 31. During this movement the lower rollers 15 are 100 guided along straps 32 onto the tracks 14. Continued movement of the cross head to the right brings the carrier and its tile to a position over the platform 10.

When the carrier moves again to the left, 105 the tile must be left deposited on the platform. A lever 33 is pivoted at 34 and a downwardly projecting end 35 thereof is

adapted to engage and hold the tile from returning with the carrier. The lever is automatically tilted in both directions about its pivot by mechanism now to be described. 5 Weights in the form of rollers 36 are provided on the lever for aiding in its movement, these weights being confined to the lever by the crooks 37 at the lever ends. At the end of the left hand movement of the 10 carrier, rollers 38 on the sides thereof engage against abutments 39, whereby the carrier is tipped to its vertical tile receiving position.

In Fig. 2, the end 35 of the lever is illustrated as engaging behind the board 4 of the tile in the carrier, the weights 36 holding the same in place. When the carrier moves to the left, the tile will be held from movement therewith. Just before the carrier reaches the position shown in Fig. 1, the free end of an arm 40 carried by the shaft 23 engages against the right hand end of the lever 33 and tips the lever to the position shown in Fig. 1, whereupon the weights 25 36 roll to the right hand end of the lever. This movement is limited by a stop 41.

Upon movement of the carrier to the right, a plate 42 carried by the cross head 26 engages against a lever 43 pivoted at 44 30 and moves such lever to the right against the action of a spring 45. Another arm 46 of lever 43 is connected by a link 47 to an arm 48 pivoted at 49. An arm 50 has one end pivoted at 49 and its free end engaging 35 beneath the right hand end of lever 33. An arm 51 is connected rigidly to the arm 48 and is connected to the arm 50 by a spring 52. Through this connection, the lever 33 is pivoted to the left upon movement of the 40 cross head to the right. It will be noted that both ends of the link 47 are adjustably connected to the arms 46 and 48.

When the lever 33 is pivoted to the left, the weights 36 roll to the left hand end of 45 the lever. To prevent the left end 35 from engaging and marring the tile, I provide a lug 53 on the lever and a cooperating plate 54 on the carrier. The lug engages the plate and sustains the weight of the lever until 50 the carrier has reached a position wherein the end 35 will drop back of the board 4.

It is believed that the construction and operation of my machine will be clear without further description herein. The machine operates continuously and automatically, the crank arrangement providing sufficient pause at each end of the travel of the carrier to permit the loading and unloading thereof.

60 Having thus described my invention, what I claim is:

1. A conduit turning machine comprising the combination of a conveyor, a horizontal platform spaced therefrom, a conduit receiving carrier, power means for reciprocally

moving the carrier to and between the conveyor and platform, the carrier when adjacent the conveyor being adapted to receive a conduit in the upright position from the conveyor, and means cooperating with the power means for tipping the carrier to deposit the conduit onto the platform in a horizontal position.

2. A conduit turning machine comprising the combination of a conveyor, a horizontal 75 platform spaced therefrom, a conduit receiving carrier, power means for reciprocally moving the carrier to and between the conveyor and platform, the carrier when adjacent the conveyor being adapted to receive a conduit in the upright position from the conveyor, means cooperating with the power means for tipping the carrier to deposit the conduit onto the platform in a horizontal position, and means automatically engaging 80 the conduit to prevent movement thereof from the platform when the power means returns the carrier.

3. A conduit turning machine comprising the combination of a conveyor, a horizontal 90 platform spaced therefrom, a track therebetween, a conduit receiving carrier having means supporting the same on the track, power means for reciprocally moving the carrier on the track to and between the conveyor and platform, means for cooperating 95 with the carrier and track for tipping the carrier to a vertical position when adjacent the conveyor whereby the carrier can receive a conduit in the upright position from the conveyor and for tipping the carrier back to the horizontal position upon movement in the opposite direction whereby to deposit the conduit on the platform in a horizontal position.

4. A conduit turning machine comprising the combination of a conveyor, a horizontal platform spaced therefrom, a conduit receiving carrier, a track above the carrier, a cross head thereon having pivotal connection with the carrier, power means connected to and adapted to reciprocate the cross head to move the carrier to and between the conveyor and platform, and means cooperating with the carrier and power means for tipping the carrier to a vertical position when adjacent the conveyor whereby the carrier can receive a conduit in the upright position from the conveyor and for tipping the carrier back to the horizontal position upon movement in the opposite direction whereby to deposit the conduit on the platform in a horizontal position.

5. A conduit turning machine comprising the combination of a conveyor, a horizontal platform spaced therefrom, a conduit receiving carrier, power means for reciprocally moving the carrier to and between the conveyor and platform, the carrier when adjacent the conveyor being adapted to receive 125

a conduit in the upright position from the conveyor, means cooperating with the power means for tipping the carrier to deposit the conduit onto the platform in a horizontal position, means for engaging the conduit to prevent movement thereof from the platform when the power means returns the carrier, and means for automatically moving the third named means to the conduit when the carrier with a conduit thereon has been moved to the platform and for automatically moving the said means away from the conduit after the carrier has left the conduit.

6. In combination, a conduit extruding die, a conduit handling machine, a conveyor beneath the die and extending to the said machine, and a conduit receiving support beneath the die and movable vertically through an opening in the conveyor, the support being of a size to pass downwardly through the said opening and being adapted to receive a conduit from the die and deposit the same on the conveyor at the said opening from whence the conduit is carried to the said machine.

GEORGE F. PEMBERTON.
